UNITED STATES PATENT OFFICE.

THOMAS EDGAR AUD, OF HERNDON, VIRGINIA, ASSIGNOR TO THE AUD COMPANY, INCORPORATED, OF LEESBURG, VIRGINIA.

LIFE-SAVING SUIT.

Application filed February 23, 1927. Serial No. 170,269.

This invention relates to certain new and useful improvements in life saving suits, and has particular reference to a novel construction of the suit and means for closing an entrance opening therein, whereby a suit of simple construction is provided which may be easily and quickly put on and taken off and whereby a quick and water-proof closure of the entrance opening may be effected.

10 The object of the invention is to provide a suit for life saving, swimming and analogous purposes, which may be applied with great ease and speed and which will effectually seal the entrance opening against the intrusion of water.

The invention consists of the features of construction, combination and arrangement of parts, hereinafter fully described and claimed, reference being had to the accompanying drawings, in which:

Figure 1 is a front view of the suit as applied for use and showing the wearer in the act of operating the closure slide for a closure action.

25 Figure 2 is a similar view showing the closure slide in closing position.

Figure 3 is a front view on an enlarged scale of a portion of the garment and the closure slide.

30 Figure 4 is a cross-section on line 4—4 of Figure 3.

Figure 5 is a cross-section on line 5—5 of Figure 3.

35 Figure 6 is a rear elevation of the closure slide.

Figure 7 is a perspective view of the same.

Figure 8 is a front elevation of a suit showing the application of the invention for closing a different arrangement of entrance opening.

40 Figure 9 is a front view of the suit employing the construction fragmentarily shown in Figure 8.

Figure 10 is a detail view of the lower portion of the suit shown in Figure 9.

45 Figure 11 is a cross-section through the lower ends of the sealing strips shown in Figures 8, 9 and 10.

Figure 12 is a detail view of the clip.

50 Referring to the drawings, and particularly to Figures 1 to 7, thereof, 1 designates a life saving suit of integral or union type, in which the trousers portion 2 and jacket portion 3 of the suit are permanently connected. The legs of the trousers portion 2,

as shown, terminate in foot portions, socks or boots 4, while the jacket portion 3 is provided with sleeves 5 terminating in gloves or mittens 6. The suit as thus constructed is adapted to receive and envelop the person of the wearer from feet to neck, and its jacket portion is provided with a suitable neck band 7. All these portions of the suit are made of some suitable strong and durable water-proof material, such as soft vulcanized rubber or any suitable combination of rubber and fabric, any seams used for uniting the parts where necessary being of water-tight character.

The suit is provided with an entrance opening 8 extending horizontally or transversely across the front of its jacket portion from side to side of the jacket, the ends of said opening terminating just below the arm pits. This opening divides the front portion of the jacket into an upper part or breast portion 9 and a lower part or abdominal portion 10. This breast portion 9, the companion part of the back of the suit, the sleeves 5 and the neck band 7 are thus adapted to swing or hinge backwardly on the back portion of the suit as a hinge member, or, in other words, the upper part of the suit above the horizontal line of the lower meeting edge of the opening 8 may be swung downward parallel with the back of the suit below such horizontal line, so that the remainder of the garment below said horizontal line will be accessible through the opening 8. When the above-mentioned upper part of the suit is thus swung backwardly, the person desiring to don the suit may step into the trousers portion and lower half of the jacket portion through the opening 8 and draw such portions of the suit upwardly upon him, after which he may pull the downturned upper portion of the suit upward over his shoulders and head and insert his arms into the sleeves 5 and pass his head through the opening of the neck band 7, thus fully fitting the suit upon his person so that, upon the closure of the opening 8 in a water-tight manner, the body of the person between the feet and neck will be enveloped in a garment impervious to the entrance of water. In practice, the suit is made of such size and of such fullness so that a suit of any certain size will fit persons within certain height and weight ranges, the size and fullness of the suit being also

such as to permit the suit to be applied in the manner described. The neck band 7 may be of elastic character so that it will closely hug the neck and automatically adjust itself to fit necks of different sizes. In connection with the suit a head covering or helmet, not shown, of any suitable type may be used to give such protection to the head or head and face of the wearer as may be desired.

A sealing and fastening means is employed for closing the entrance opening 8 in a water-tight manner. To this end, locking and sealing strips 11 and 12 are provided which extend the distance respectively of the upper and lower marginal edges of the entrance opening. These strips are provided with marginal flanges 13, integral therewith, and which are secured to the meeting edges of the garment forming the marginal edges of the opening in any secure and water-tight manner. The strips 11 and 12 and their flanges are of semi-flexible character, having a sufficient degree of stiffness for form sustaining purposes and a certain degree of flexibility to adapt them to accommodate themselves to the movements of portions of the suit under the movements of the wearer as well as to be brought into close sealing contact and to interlock for a fastening action, as hereinafter described. For the purposes mentioned, the strips may be made of semi-vulcanized rubber, or a mixture of rubber and fibre, or molded rubber and fabric. The strips have broad contacting sealing faces, and the sealing face of one strip is provided with a longitudinally extending locking and sealing rib or tongue 14 to engage a longitudinally extending locking and sealing groove 15 opening through the meeting face of the other strip. The rib or tongue and the groove are of angular form in cross-section, each being of greatest width centrally of its depth, or the groove and tongue being of uncut or dovetailed construction so as to effect a combined locking and sealing action. In the present instance the groove and rib or tongue are of hexagonal form in cross-section, so that when the tongue is forced under pressure through the narrow outer side of the groove and seats fully in the groove the overhanging walls of the outer side of the groove will overlap the inner walls of the tongue and thereby provide a locking connection which will prevent the tongue from being withdrawn or displaced from the groove unless a comparatively great degree of extracting force is used.

A pressure applying and locking device 16 is employed for forcing the strips together and the rib 14 into the groove 15, so as to effect a sealing of the opening 8, and for holding the strips in sealing relation. This pressure applying and locking device com-

prises a block or body of generally oblong rectangular form closed at its outer side and open at each end and at its inner side so as to receive and snugly embrace the strips 11 and 12. The space between the three walls 70 of the block provides a channel in which the strips are received, and this space or channel is beveled or flared in one direction, by proper formation of the top and bottom walls of the block, which give the channel a 75 wedge formation and provide wedge surfaces or walls for forcing the strips 11 and 12 together when the block is moved in one direction. The top and bottom walls of the block are provided at their inner sides with 80 inturned guide and retaining flanges 17, projecting partially across and narrowing the open side of the block to form a wedge-shaped slot, and these flanges 17 slidably engage guide grooves 18 formed in the sealing strips adjacent to the flanges 13, whereby the block 16 is slidably mounted on the strips and held thereon from outward displacement. A suitable handle or gripping projection 19 is provided upon the outer side of the block 90 whereby it may be manipulated for a sealing and locking action and for retraction whenever it is desired to effect an unlocking and unsealing action.

Figure 1 shows the suit applied for use 95 and illustrates the manner in which the block 16 is adjusted for a sealing and locking action. In its normal position the block 16 lies at one end of the opening 8, that is to say, at one side of the front of the suit shown in Figures 1, 2 and 3. This block is gripped in one hand of the operator and slid across the strips 11 and 12 until it reaches a final position at the other end of the opening, namely, at the opposite side of the front of the suit. As the block is thus moved along the strips its wedge surfaces force the strips 11 and 12 together and thereby force the tongue or rib 13 into the groove 15 until, when it reaches its final position, the sealing faces of the strips are brought into intimate contact and the tongue interlocked with the groove the full length of the strips, thereby closing the opening 8 and sealing the joint between its meeting edges in such a manner as to effectually prevent the intrusion of water. As the strips are made of semi-elastic rubber, it will be apparent that, in addition to the closed joint between the meeting faces of the strip, 115 which are tightly bound together, the walls of the tongue and groove will be interlocked under pressure and will thereby form an additional obstruction or dam against the passage of water, whereby a leak-proof joint is 120 effected. Owing also to the elasticity of the strips, and the tightness of the interlocking connection, flexibility of the strips along their entire length in the movements of the 125 suit, under the body movements of the 130

wearer, will be permitted without the strips separating and breaking from sealing connection, as a force much greater than the ordinary service force falling thereon must 5 be employed in order to effect an unlocking action or separation of the strips. Consequently the suit may be immersed for long periods in water without leakage, and, as the suit as a whole, including the block, may be 10 made of rubber, a construction of fastening connections will be provided which will be proof against rust or other actions of fresh or salt water. It is to be understood, of course, that if desired the ribs and block may 15 be reinforced by the use of strips of resilient metal embedded therein in the event that, under such conditions, additional stiffness and resiliency is found to be necessary.

Instead of employing a single block 16, I 20 may employ a plurality of such blocks 16, as shown in Figure 8, spaced desired distances apart and flexibly united by link members 20 so that a compound pressure applying and locking device will be provided in which, when said device is fully 25 applied, the block 16 of the series will be disposed at different points along the length of the strips. This construction of the pressure applying and locking device may be 30 used under conditions where the suit is liable to be subjected to severe service strains or in order to provide locking means which will absolutely obviate any possibility of the sealing strips separating at any 35 point under service conditions.

In Figures 9 to 12 I have shown a slightly modified construction of life saving suit in which the entrance opening 8^a extends vertically between the crotch and neck portions 40 of the suit, instead of transversely of the suit. The construction of the sealing strips extending along the margins of this opening 8^a is the same as that heretofore described, but on account of the length of this opening 45 8^a it is considered desirable to either employ a plurality of individual blocks 16 for pressure applying and locking actions, which will be located at different points along the opening when the latter is enclosed, or to 50 employ a compound type of pressure applying and locking device of the character shown in Figure 8, in which the linkage connection allows of the blocks to be simultaneously adjusted instead of requiring independent adjustments as with the individual 55 blocks. The construction and mode of use of this modified form of suit will be obvious from the foregoing description.

In either form of the invention the sealing strips 11 and 12 are preferably united at the starting end as shown in detail in Figures 11 and 12. These ends of the strips preferably extend a distance beyond the starting end of the opening 8 or 8^a and may 65 be clamped together by a clip 21 having

spurs 22 embedded in the strips. A fastener 23 may also be passed through the strips with it sends pinched to hold the parts firmly connected.

It will thus be seen that my invention 70 provides a type of life saving suit which may be applied for use with great ease and in a quick and convenient manner, and that such suit is free from a complexity of parts liable to cause confusion in the mind of a person 75 about to put it on as to how it should be put on, and that when applied the entrance opening 8 or 8^a, as the case may be, may be sealed by a quick and practically instantaneous closing movement. It is to be understood, of course, that the suit may be provided with any suitable type of means for making it buoyant, and of such sufficient buoying qualities to keep the wearer afloat for an indefinite period, so that as long as 85 the suit remains intact and is kept sealed the wearer will be sustained in the water. The suit is therefore admirably adapted for life saving purposes on shipboard in the case of sinking of a ship or other disaster, as well 90 as for the use and aid of swimmers in swimming long distances through rough and icy water, as the suit will not only keep the wearer afloat but protect him from cold and other actions of the elements. The suit may 95 be equipped in practice with suitable means for holding food and other provisions of a suitable character to sustain life or to afford refreshment while the wearer is in the water.

While the construction disclosed is preferred, it will, of course, be understood that changes in the form, arrangement and details of construction of the parts may be resorted to within the scope of the appended 105 claims without departing from the spirit or sacrificing any of the advantages of the invention.

Having thus fully described my invention, I claim:—

1. A life saving suit having an entrance opening, closure strips along the marginal edges of said opening having sealing faces, sealing means on said faces adapted to interlock when closing pressure is applied to said strips to prevent separation of the faces to maintain the same in leak-proof engagement, and means operative on said strips for applying closing pressure thereto.

2. A life saving suit having an entrance opening, closure strips along the marginal edges of said opening exteriorly of the suit, said strips having sealing faces, sealing means on said faces adapted to interlock when closing pressure is applied to said strips, and means longitudinally of and on said strips for applying closing pressure thereto.

3. A life saving suit having an entrance opening, elastic closing strips along the

marginal edges of said opening, one having a groove and the other having a tongue to interlock with the groove when closing pressure is applied to said strips, and a wedge 5 fastener slideable on said strips for applying closing pressure thereto.

4. A life saving suit having an entrance opening, closure strips along the marginal edges of said opening, said strips having 10 sealing faces and interlocking and sealing means located intermediately of said faces for engagement to hold the faces in contact when pressure is applied to said strips, and a wedge fastener slideable on said strips 15 for applying closing pressure thereto.

5. A life saving suit having an entrance opening, closure strips along the marginal edges of said opening having sealing portions 20 adapted to interlock when closing pressure is applied to said strips from one end to the other of the same, and means for progressively applying pressure to the strips to force said sealing portions into interlocking engagement.

25 6. A life saving suit having an entrance opening, closure strips along the marginal edges of said opening, one having a groove and the other a tongue to engage the groove, the groove and tongue being of angular 30 cross-section for an interlocking action when engaged, and means for forcing said strips together into sealing contact and to cause an interlocking engagement between the tongue and groove.

35 7. A life saving suit having an entrance opening, closure strips of elastic material extending along the marginal edges of said opening, said strips having sealing faces, and one of said strips having a groove and 40 the other a tongue to interlock with the groove, the groove and tongue being of angular form in cross-section for an elastic sealing and locking engagement only when the strips are forced together, and means for 45 forcing the strips together under pressure into sealing engagement and to cause an interlocking action between the tongue and groove, said means operating to hold the parts connected against displacement.

50 8. A life saving suit having an entrance opening, closure strips extending along the marginal edges of said opening and provided with guide grooves, one of said strips having a locking groove and the other of said strips 55 having a locking tongue to engage said groove, the groove and tongue being of angular form in cross-section for an interlocking connection when engaged, and a sliding fastener embracing the strips and slidingably engaging the guide grooves and having 60 surfaces operative to force the strips together

and the locking tongue and groove into interlocking engagement.

9. A life saving suit having an entrance opening, elastic closure strips attached to 65 and extending outwardly at right angles from the marginal edges of said opening, said strips having broad sealing faces, one of said strips having a locking groove opening through its sealing face and the other 70 of said strips having a locking tongue for engagement with said groove, the tongue and groove being of angular cross-section for an interlocking action when engaged, and a sliding fastener engaging the strips 75 and operative for applying a forcing pressure for bringing their sealing faces together and causing an interlocking engagement between the groove and tongue.

10. A life saving suit having an entrance 80 opening, closure strips along the marginal edges of said opening having sealing faces and joint closing and locking means upon said sealing faces, and a series of link fasteners slidably engaging said strip and operative 85 when moved in one direction thereon for forcing the strips into sealing and locking engagement.

11. A life saving suit having an entrance opening, closure strips along the marginal 90 edges of said opening, and joint closing and locking means upon said strips adapted to interlock when the strips are brought under pressure.

12. A life saving suit having an entrance 95 opening, closure strips along the marginal edges of said opening having sealing faces adapted to be brought into abutting engagement, and joint closing and locking means upon said sealing faces adapted to 100 interlock when the sealing faces are brought into abutting engagement.

13. A life saving suit having an entrance opening, closure strips along the marginal edges of said opening having sealing faces, the sealing face of one strip being provided 105 with a groove, and a tongue upon the sealing face of the other strip adapted to engage and interlock with said groove when the sealing faces of the strips are brought into 110 sealing relationship.

14. A life saving suit having an entrance opening, closure strips along the marginal edges of said opening, one of said strips having a groove and the other a tongue to 115 engage the groove when the strips are brought into closing relationship, said groove and tongue being of polygonal cross-section for an interlocking action when engaged.

In testimony whereof I affix my signature.
THOMAS EDGAR AUD.
